UNITED STATES PATENT OFFICE.

HERBERT BANKE, OF MAYWOOD, ILLINOIS, ASSIGNOR TO AMERICAN CAN COMPANY,
OF NEW YORK, N. Y., A CORPORATION OF NEW JERSEY.

SIDE-GAUGE-LOCKING DEVICE FOR SLITTERS.

Application filed October 16, 1922. Serial No. 594,944.

To all whom it may concern:

Be it known that I, HERBERT BANKE, a citizen of the United States, residing in Maywood, in the county of Cook and State of Illinois, have invented a new and useful Improvement in Side-Gauge-Locking Devices for Slitters, of which the following is a specification.

This invention relates to sheet metal slitting machines and more particularly to means in such machines for preventing delivery of the sheets to the cutting, or slitting elements until completely squared up, or aligned.

The invention contemplates a construction in which gauging devices are employed at the side as well as at the front of the table across which the sheets are fed and has for a principal object the provision of means for preventing delivery of a sheet to the cutters without its first coming into contact with both the side and front gauging devices.

It is also a purpose of the invention to provide a practical and economical means for automatically insuring proper alignment of the successive sheets as they are fed into the machine.

Other objects and advantages of the invention will be apparent as it is better understood from the following description, which, taken in connection with the accompanying drawings, discloses a preferred embodiment thereof.

Referring to the drawings,

Figure 1 is a plan view, partly broken away, of a slitting machine in which my invention is embodied;

Fig. 2 is a detail view of the gearing employed for operating the cutter shafts, and showing also the rock shaft bearing;

Fig. 3 is a sectional view taken substantially on the line 3—3 in Fig. 1 and showing a front gauging finger and its associated locking mechanism;

Fig. 4 is a detail section taken through the upper part of one of the gauging fingers, showing its adjustable mounting;

Fig. 5 is a section taken substantially on the line 5—5 of Fig. 1 and showing the lock-

ing mechanism associated with the side gauge; and

Fig. 6 is a view taken substantially on the section line 6—6 in Fig. 1.

The apparatus illustrated on the drawings comprises a table 11, which is suitably supported from the floor and upon which the operating mechanism of the machine is mounted. The slitting mechanism comprises a series of rotary knives 12 and 13, which are mounted respectively on horizontal shafts 14 and 15, which shafts are driven by means of a pulley 16 which is mounted on the lower shaft 14. A gear 17 on said shaft 14 meshes with a second gear 18 on the shaft 15, whereby both said shafts are driven in desired manner to accomplish the cutting action. A rock shaft 19 is mounted above the cutters, having bearings in extensions 20 of brackets 21 and 22. Front gauging fingers 23 are adjustably mounted upon this shaft, being secured by a set screw 24 and clamping screws 25 and 26 to a block cam 27 which is clamped upon said shaft by means of a bolt 28. Said cam is provided at the front with a guideway in which the upper vertical end 29 of a finger 23 is mounted, and said end 29 is provided with a slot 31 permitting adjustment thereof.

A guard 32 is secured to the table 11 near the front thereof and is provided at the top with a grooved guide 33 in which are adjustably secured brackets 34 to which locking fingers 35 are pivotally attached at 36. One of said locking fingers is associated with each gauging finger 23 and their function will be apparent upon inspection of Figure 3. It will be noted that the fingers have their upper ends held in contact with a shoulder 37 on the block 27 by means of a spring 38, and thus prevent rotation of the shaft 19 until disengaged from said shoulder by means of an advancing sheet bearing against the lower ends 39 of the fingers which are disposed in the path of the sheets and in advance of the gauging fingers 23. Since either of the locking fingers 35 will serve to prevent rotation of the shaft 19, it is obvious that a sheet must act upon each

of them in order to permit it to pass and thus the front edge must be square before a sheet can be delivered to the rotary cutters 12 and 13. The rotation of the shaft 19 under the influence of the gauge fingers 23 is yieldingly resisted and the shaft returned to normal position by a spring 30 secured at one end to an arm 40 on said shaft and at the other end to the frame.

10 I also provide a side gauging device, which consists of a lever 41 pivoted at 42 to a bracket 43 which is adjustably secured to the table 11. In order that a sheet may have its proper lateral position, it is necessary that it contact with this side gauging device, as well as the front gauging fingers 23 and I, therefore, provide means for insuring such contact before the sheet can pass. This means comprises a vertical locking bar 44, which is pivotally connected at 45 to an extension of the bracket 43 and is normally pressed away therefrom by means of a leaf spring 46. Said bar 44 is disposed beneath an arm 47 which is secured upon the shaft 19 by means of a screw bolt 48. When in this position, rotation of the shaft 19 is prevented by the side locking device, as well as by the fingers 35.

15 20 25 30 35 40 45

Referring now to Fig. 6, it will be observed that when a sheet, indicated in this figure by the character 49, comes in contact with the lever 41, said lever acts upon a projection 51 on the lower part of the bar 44 and forces said bar against the tension of the spring 46 from beneath the arm 47, thus releasing the shaft 19. When the sheet has then released the front locking mechanism, by contact with the separate fingers 35, the rock shaft 19 may rotate under the influence of the gauging fingers 23, which are provided at their lower ends with rollers 52 and adapted to be lifted by the force of the advancing sheet. Table extensions 53 are provided adjacent said gauging fingers 23 and serve to support the sides of the sheet as it passes between the rotary cutters.

From the foregoing, it will be manifest that a sheet must be brought first into contact with the side gauge 41 and then with the front gauges, before the shaft 19 can be rotated, and thus accurate alignment is insured at the time the sheet is delivered to the cutters. A spring 54 is provided between the forward end of the lever 41 and the bracket 43 and serves to normally hold said lever in its outer position while permitting it to recede under the influence of a moving sheet. This spring permits the passage of an irregular sheet portion after the front of the sheet has been engaged by the cutters and also normally holds the bar 44 in its locking position.

It is thought that the invention and many of its attendant advantages will be understood from the foregoing description, and

it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. In a sheet metal slitting machine, the combination of slitting elements, a table supporting the sheets as they are fed to said elements, front and side gauging devices for squaring the sheets upon said table, and locking means for said gauging devices requiring contact by the sheets with each of said devices prior to their being advanced to said cutting elements.

2. In a sheet metal slitting machine, the combination of slitting elements, a table across which the sheets are fed to said elements, gauging devices adapted to engage edges of the sheets, which edges are angularly disposed relative to each other, and means for preventing advance of the sheets to the slitting elements until after they have acted upon each of said devices.

3. In a sheet metal slitting machine, the combination of slitting elements, a table across which the sheets are fed to said elements, gauging devices at the front of the table, means for locking said devices to prevent passage of a sheet except upon contact with each thereof, side gauging means, and locking means preventing the advance of a sheet to the slitting elements without contact with said side gauging means.

4. In a sheet metal slitting machine, the combination of slitting elements, a support across which the sheets are fed to said elements, and means for squaring the sheets upon said support, said means comprising a plurality of front gauging fingers, and a side gauging device, and means requiring contact of a sheet with each of said fingers and said device prior to its being advanced to the cutting elements.

5. In a sheet metal slitting machine, the combination of slitting elements, a support across which the sheets are fed to said elements, a plurality of gauging devices adapted to engage edges of an advancing sheet, which edges are at an angle to each other, and means requiring contact of a sheet with each of said devices prior to its entry into the slitting elements.

6. In a sheet metal slitting machine, the combination of cutters, a table upon which the sheets are advanced to said cutters, a plurality of gauging fingers supported above said table near the front thereof, a rock shaft upon which said fingers are supported, gauging means at the side of the table, and means for preventing rotation of said rock shaft to remove said front gauging fingers from the path of the sheet, except

upon contact of said sheet with both said side gauging means and said fingers.

7. In a sheet metal slitting machine, the combination of cutters, a table upon which the sheets are advanced to said cutters, a plurality of gauging fingers supported above said table near the front thereof, a rock shaft upon which said fingers are sup-

ported, means associated with each of said fingers for preventing rotation of the shaft ¹⁰ except when a sheet acts upon said fingers simultaneously, side gauging means, and means for preventing rotation of said shaft unless the sheet acts also upon said side gauging means.

HERBERT BANKE.
